UNITED STATES PATENT OFFICE

2,534,462

CUSHION INSOLE

Henry G. Lumbard, Auburn, Maine

Application July 22, 1949, Serial No. 106,285

3 Claims. (Cl. 36—76)

1

This invention comprises a new and improved flexible insole of the cushion type. The principal object of the invention is to provide a cushion insole that may be conveniently prepared and furnished to the shoemaker as a complete unit having a continuous cushion layer, which in the finished shoe will lie beneath the foot of the wearer, also having the desired shank curvature made permanent in the insole by an attached metallic shank stiffener, and presenting a pair of through-and-through perforations by which the insole and stiffener may be riveted into the finished shoe bottom.

A highly desirable riveted shank construction is disclosed in my prior Patent No. 2,391,789, dated December 25, 1945, and directed to a process of making cushion sole shoes. In the process of that patent, however, it is necessary to feel for a rivet hole which is concealed in the insole by a continuous cushion ply. This involves a slow and somewhat uncertain step that is obviated by employing the improved insole of the present invention.

Going more into detail, I have invented a cushion insole comprising co-extensive plies of fibreboard and cushion material united with full shank curvature, the fibreboard having a transversely slotted and very flexible forepart and a stiff toe and heel area, and a curved metallic shank stiffener attached to the shank portion of the fibreboard ply and imparting its curvature thereto, the said stiffener having a perforation near each end and body plies of the insole having corresponding registering perforations therein whereby rivets may be freely introduced through the insole and stiffener of a shoe lasted upon the insole.

The registering perforations may be conveniently formed by a punch arranged to operate through the perforations of the metallic stiffener which thus serves as a jig. This not only insures accurate registration of the perforations in the plies of the insole with the perforations of the shank stiffener, but it has been found that a punch operated in this manner will form a hole in the cushion area that is larger than that in the fibreboard layer, thus affording a recess in which the upset flange of a rivet may be seated below the plane of the face of the cushion ply.

These and other features of the invention will be best understood and appreciated from the following description of a preferred embodiment thereof, selected for purposes of illustration and shown in the accompanying drawings in which:

Fig. 1 is a plan view of the insole unit as seen from beneath.

2

Fig. 2 is a corresponding view of the insole unit as seen from above,

Fig. 3 is a corresponding view in side elevation,

Fig. 4 is a view in cross-section on the line 4—4 of Fig. 2, and

Fig. 5 is a fragmentary view of a shoe bottom in longitudinal section.

In preparing the improved cushion insole of my invention the fibreboard ply 10 is first cut accurately to size and shape and is provided in its forepart area with a series of through-and-through transverse slits 11. These are staggered with respect to each other and some of them intersect the marginal edges of the ply. The edges of the slits 11 are slightly separated so that the area of the insole in which they are included is extremely flexible. The toe end 12 of the fibreboard ply and the shank and heel seat portions thereof are left unslotted and in stiff but moldable condition.

Having completed the shape of the fibreboard ply 10, its shape is exactly duplicated in a cushion ply 13 which may preferably consist of a composition of ground cork and rubber, although any cushion material would serve as well for purposes of the present invention. The cushion ply 13 is permanently united in continuous face-to-face contact to one face of the fibreboard ply 10, covering the slits 11 and furnishing a smooth surface which will be located beneath the foot of the wearer in the finished shoe.

The fibreboard ply may now be gauged and marked for the reception of a curved metallic shank stiffener such as the stiffener 14 shown in the drawings. The shank stiffener is curved somewhat transversely and constitutes a stiff and rigid member in the shoe bottom. It has the full longitudinal shank curvature required in the finished shoe, and when attached to the fibreboard ply by split rivets 15 or other equivalent fastenings, it imparts permanently to both plies of the insole the shank curvature desired in the finished shoe.

The composite insole unit may now be presented to a punch of a size to pass freely through the perforations 16 of the shank stiffener as shown in Figs. 1 and 4. In its operation the location of the punch is positively fixed by the perforations in the shank stiffener as if the latter were a jig. Each hole made in the fibreboard ply 10 registers exactly with the corresponding perforation 16 of the shank stiffener and is of the same diameter. On the other hand, in operating on the cushion ply 13, the material is temporarily compressed and the resulting perforations 17 are

substantially greater in diameter than the perforations in the fibreboard 10 although they are accurately located in concentric relation therewith. The complete insole unit as shown in the drawings presents the enlarged recesses 17 in its cushion face, while the prongs of the rivets 15 are imbedded in the cork ply and sunk beneath its surface so that the latter is perfectly smooth to the touch.

The complete insole unit, with its perforations as shown, may be supplied to the shoemaker preparatory to the lasting step. The manufacturing processes then proceed in the conventional manner prior to the attaching of the heel. While the shoe is in the lasting room it is presented to a riveting machine which drives a rivet 22 through an outsole 20 which has then been incorporated in the structure of the shoe, through the rear hole 16 of the shank stiffener 14, and then through the registered perforations in the fibreboard and cushioned plies 10 and 13. The upset inner end of the rivet 22 forms a flange resting upon the upper surface of the fibreboard ply 10 and is contained within the compass of the relatively large perforation 17, the result being that no portion of the rivet extends above the plane of the cushion ply 13. Subsequently a heel 23 is attached in conventional fashion and the bottom is finished. The usual bottom filler is indicated at 19.

When the shoe reaches the packing room and prior to the time the sock lining is inserted, a second rivet 21, having a solid head, is driven through the material of the outsole 20, through the forward hole 16 of the shank stiffener 14 and then through the registered perforations in the fibreboard and cushion plies 10 and 13. As before, the upset flanged inner end of the rivet 21 is entirely contained within the large perforation 17 in the cushion ply 13 so that the rivet does not in any way form a projection interfering with the smooth surface of the cushion ply. It is to be noted that the outsole 20 is not punched prior to the insertion of the rivets. The riveting machine forces the rivets through the material of the outsole and in this process cuts a cylindrical plug which remains in compressed condition in the barrel of the rivet. The plug thus formed serves as an effective seal preventing moisture from entering the interior of the rivet and thereby preserving it against corrosion. The head of the rivet 21 remains visible in the shank portion of the outsole and may be finished so that it provides an ornamental appearance and also an indication that the purchaser is securing a shoe of riveted shank construction.

When it is desired to insert a rivet, the pilot of the machine is inserted in the hole freely exposed in the insole and the machine tripped. The rivet is thereupon driven through the outsole from the outside, punching its own hole and being guided into the hole in the insole by the pilot of the riveting machine. The leather punched by the rivet is forced into the inside

of the barrel of the rivet and, as previously stated, remains there permanently. The rivet is clenched inside the shoe and the clenched end seated against the fibreboard of the insole. The enlarged hole in the cork ply permits clearance for the clenching operation.

When the riveting has been accomplished, a sock lining 18 is inserted in conventional manner; in addition to its usual functions the sock lining serves to cover the inner ends of the rivets 21 and 22.

Having thus disclosed my invention and described in detail an illustrative embodiment thereof, I claim as new and desire to secure by Letters Patent:

1. An improved cushion insole comprising co-extensive plies of an insole and a cushion material united with full shank curvature, the insole having a transversely slotted flexible forepart and stiff toe end area, and a curved metallic shank stiffener, fasteners attaching the shank stiffener to the shank portion of the insole ply and imparting its curvature thereto, said stiffener having a perforation located near each end independently of said fasteners and both plies of the insole having corresponding registering perforations therein whereby rivets may be introduced through the insole and stiffener of a shoe lasted upon the insole.
2. An insole of the character described in claim 1 in which the perforations in the cushion ply are of greater diameter than the perforations in the insole, thus providing a recess in which a rivet flange may be seated below the plane of the face of the cushion ply.
3. An improved shoe comprising an insole, a ply of cushion material united with the upper surface of said insole, a curved metallic shank stiffener, split rivets securing the shank stiffener to the shank portion of the insole and imparting its curvature thereto, said stiffener having a perforation located near each end independently of the split rivets and both the insole and the cushion ply having corresponding larger concentric perforations, an outsole secured to the lower surface of the insole, a pair of rivets uniting said outsole and insole and extending through the perforations in said shank stiffener and said insole, said rivets having their clenched ends entirely contained within the perforations of said cushion ply, and a plug of outsole material disposed in compressed condition in the barrel of each of said rivets.
